DISPATCHING MECHANISM FOR ALARM SIGNAL SYSTEMS

Ferdinand F. Humphreys, Caldwell, N. J., assignor to Signal Engineering & Manufacturing Company, New York, N. Y., a corporation of Massachusetts

Application November 14, 1941, Serial No. 419,097

4 Claims. (Cl. 177—360)

The present invention relates to alarm signal systems, particularly fire alarm systems employing a number of bells or other signal devices adapted to be sounded or otherwise operated in response to the actuation of any one of a number of separate alarm sending stations, such systems being commonly installed in schools, factories, hotels and other large buildings.

In Wheelock Patent No. 2,238,144, issued April 15, 1941, there is shown and described an alarm signal system of the above indicated character, in which the actuation of a sending station is adapted to operate the signals through a number of code sequences, determined by the designation of the actuated station. While generally speaking, the signals cease to operate on a code basis after a station has run down, the aforesaid patent also discloses manually operable means at each station for causing operation of the signals on a continuous non-code basis, through functioning of an impulse transmitting device. Furthermore, in Wheelock & Humphreys Patent No. 2,250,054, issued July 22, 1941, there is shown and described a dispatching mechanism for a signal code sending station, characterized by the provision of means for automatically closing the coding the coding contacts of an actuated station after the latter has run down, to cause operation of the signals on a continuous basis.

The present invention relates particularly to a modification of the dispatching mechanism shown in the aforesaid Wheelock & Humphreys patent, wherein initial actuation of a sending station automatically closes contacts in the form of a knife switch, which closure has the immediate effect of shunting out the resistor that normally restricts the current traversing the master controller of the system to a supervisory level. Thereafter, while this switch remains closed, successive opening and closing of the coding contacts of the actuated station will serve to transmit a predetermined number of rounds of code sequences, followed by automatic functioning of the impulse transmitting device to operate the signals on a continuous basis, irrespective of the fact that the operating mechanism of the actuated station has run down. A further feature of the invention resides in the facility with which the above described switch contacts can be manually opened without arcing, when resetting the run down station, or can positively be prevented from closing to transmit a false alarm, when testing the operating mechanism of the station.

The above and other advantageous features of the invention will hereinafter more fully ap-

pear from the following description, considered in connection with the accompanying drawings, in which:

Fig. 1 is a schematic view, illustrating an alarm system comprising stations each embodying a dispatching mechanism of the invention, in its normal non-operating condition.

Fig. 2 is a schematic diagram similar to Fig. 1, illustrating the transmission of signals on a continuous non-code basis, through functioning of the dispatching mechanism of the present invention.

Fig. 3 is a view in rear elevation of a dispatching mechanism embodying the invention.

Fig. 4 is a side view of the parts of Fig. 3.

Figs. 5 and 6 are fragmentary views based on Fig. 4, showing parts of the dispatching mechanism in different positions.

Fig. 7 shows the parts in position for a test of the driving mechanism.

Fig. 8 is a fragmentary end view of the mechanism.

Referring first to Fig. 1, the dispatching mechanism of the present invention is shown, for purposes of illustration, as being embodied in one or more sending stations of an alarm signal system, such as is shown in the copending application of John H. Wheelock and Hugo F. Cypser, Serial No. 418,116, filed November 7, 1941. In this system, the signals 1 are shown as being of the single stroke solenoid type, with each providing an operating winding 2, within which moves a magnetic striker 2a. The windings 2 of the signals 1 are adapted to be connected in sections across supply mains 3 and 4, with balancing resistors 5 between the sections, by means of a number of sets of relatively movable contacts 6 and 7 forming part of a master controller, generally designated by the reference character A.

The controller A comprises a winding 8, with a main armature 9 movable in response to full energization of the winding to close the several sets of contacts and operate the signals 1. The controller winding 8 has one terminal thereof connected to the supply main 4, while the other terminal is connected in series with a number of alarm sending stations S disposed in various locations throughout the system. Each station S provides a dispatching mechanism, hereinafter described in detail, the operation of which is adapted to intermittently open and close coding contacts 10, in accordance with the arrangement of projections 11a on a code wheel 11. Upon actuation of a station S, the code wheel 11 is adapted to be turned through a predetermined

number of revolutions by a spring motor 12 of any desired type, such as is usually employed in fire alarm sending stations, with the motor 12 being wound upon actuation of the mechanism, as shown in Figs. 3 and 4.

The closed contacts 10 of the several stations S are connected in series with each other, and with a controlling resistor 13 by a station conductor 14. A return conductor 15 passes through all of the stations, and the conductors 14 and 15 in each station are adapted to be connected together by a short circuiting switch 16. The switch 16 is preferably in the form of a knife switch, as shown in Fig. 4, with the movable blade 16a of the switch normally out of engagement with the spaced stationary contacts 16b. As will later appear, each switch 16 is adapted to be closed immediately in response to the actuation of its station.

The several stations S are connected by a conductor 17 to the normally closed contacts 18 of an automatic circuit interrupter 19 of the type shown in Hanel Patent No. 1,968,500, issued July 26, 1932. The interrupter 19 is shown diagrammatically as consisting of a pivoted arm 20 carrying one contact 18, and connected to the free end of a thermal element 21, with the initial tension of the element 21 maintaining the contact 18 on the arm 20 in engagement with the stationary contact 18. Upon the passage of a predetermined current through the thermal element 21, its heating and expansion permits a spring 20a to turn the arm 20 about its pivot to disengage the contacts 18, whereupon current no longer flows through the element 21. The resulting cooling and contraction of the element 21 thereupon causes the arm 20 to reengage the contacts 18, and this cycle is repeated to cause the interrupter to make and break the circuit of the element 21 so long as sufficient current flows through the element to cause its heating and expansion. The fixed end of the thermal element 21 is connected in series with the signal windings 2 and balancing resistors 5 to a current limiting resistor 22, that is in turn connected to the other supply main 3. Normally, a small supervisory current traverses the parts of the system described thus far, as follows:

Beginning at the supply main 3, the supervisory current flows through resistor 22, signal windings 2 and through the thermal element 21 and normally closed contacts 18 of the interrupter 19. The current then traverses the several stations through the conductor 15 and the controlling resistor 13, after which it flows by conductor 14 through the coding contacts 10 to the controller winding 8 and other supply main 4. The value of this supervisory current is so low as to have no effect on the main armature 9, although it is sufficient to hold in the auxiliary armature 23, which serves to keep closed a pair of contacts 24, forming part of a control circuit for fault-indicating signals, such as are shown and described in the aforesaid Wheelock Patent No. 2,238,144. Therefore, all parts of the system are in a condition of supervision, ready to indicate the occurrence of a fault, or to transmit a number of rounds of code impulses in response to actuation of a station S, automatically followed by the continuous transmission of impulses on a non-code basis, as will next be described, with reference to the functioning of the dispatching mechanism of the present invention.

Referring now to Figs. 3 and 4, the dispatching mechanism embodying the invention is

shown as having been removed from the fire alarm box in which it is normally mounted. A portion of the front of the box is indicated at 25, and when the door of the box has been opened, the mechanism is adapted to be actuated by a hand lever 26, accessible from the front of the box as shown in Fig. 3. The lever 26 is mounted on a shaft 27, and turning of the lever downwardly from the position of Fig. 3, causes suitable gearing to wind up the spring motor 12. Consequently, upon release of the lever 26, the tension of the wound-up motor actuates the dispatching mechanism by causing rotation of a shaft 28 driven from the motor shaft 12a through suitable gearing 29. Code wheel 11 is mounted on the shaft 28, and the ratio of gearing 29 is such that the code wheel 11 makes several complete revolutions in response to one actuation of the lever 26 to wind the motor 12. The parts of the dispatching mechanism described thus far are usual in devices of this character, and the invention contemplates the provision within the dispatching mechanism of means for automatically causing the alarm signals to operate on a continuous non-code basis, after the mechanism has run down, as well as means for resetting the mechanism, and for making certain tests usually required in the maintenance of an alarm signal system.

As best shown in Fig. 4, the mechanism provides a coding arm 30, pivoted at 31, with a lug 32 of insulating material extending between the free ends of the normally closed contacts 10. The arm 30 provides an operating portion 33, normally received in a depression 34 below the general periphery of the code wheel 11, with the station in a non-operating condition. Upon turning of the code wheel 11 in response to actuation of the station, the portion 33 rides out of the depression 34 into the position of Fig. 5, and the resulting turning of the coding arm 30 causes the contacts 10 to open.

As previously pointed out, the switch 16 provides a movable blade 16a, which is mounted on and insulated from the end of a lever 35, pivotally mounted on the shaft 12a of the spring motor. The opposite arm of the lever 35 extends across the code wheel 11, and its end is connected to a pair of springs 36, which tend to center the lever in the position of Fig. 4, with the switch blade 16a out of engagement with the contacts 16b. In this position of the lever, a stud 37 thereon is located within a gap 38 provided in a circular cam track 39, turnable with the code wheel 11. One face of the stud 37 is inclined and is disposed opposite to a beveled edge of the gap 38, so that rotation of the code wheel shaft 28 will cause the stud 37 to ride onto the outside surface of the cam track 39, as shown in Fig. 5. The resulting turning movement imparted to the lever 35 will cause the knife switch 16 to close, and it is to be noted that this closure occurs almost immediately after the contacts 10 have been opened by turning of the coding arm 30. The net result is that the controlling resistor 13 will be shunted out of the circuit of the controller winding 8 immediately following the actuation of a sending station, and that the resistor 13 will remain shunted out of circuit as long as the switch 16 remains closed.

While the closure of the switch 16 has no immediate effect upon the controller winding 8, due to the previous opening of the coding contacts 10, these latter contacts will be closed as continued rotation of the code wheel permits the

operating portion 33 of arm 30 to enter a depression 34a in advance of the first code projection 11a. When this occurs, an energizing circuit for the controller winding 8 is established through the closed coding contacts 10 and switch 16, and the increased flow of current through the winding 8, due to shunting out the resistor 13, causes the controller armature 9 to pull in and close the several sets of contacts 6 and 7. Thus, the signals 1 are connected directly across the supply mains 3 and 4 to transmit the first impulse of the code sequence, and subsequent opening and closing of the coding contacts 10 as the portion 33 engages the several code projections and depressions therebetween, will cause the signals to transmit the code of the actuated station for a predetermined number of rounds, usually three or four. As shown, the signals will sound three impulses, followed by two additional impulses corresponding to the code designation Thirty-Two.

During rotation of the code wheel 11, the lever 35 remains in the position of Fig. 5, due to the friction between the blade and contacts of the closed switch 16, and the switch remains in this position as the code wheel 11 comes to rest, with the operating portion 33 in the depression 34. Since the coding contacts 10 are then closed, the controller winding 8 remains fully energized after transmission of the last impulse of the code sequence. With the armature 9 so held in, as shown in Fig. 2, the upper set of closed contacts 6 and 7 causes the thermal element 21 of the automatic interrupter to be connected directly across the mains 3 and 4. The resulting continued flow of current through the thermal element 21, as contrasted to the discontinuous flow during the transmission of code impulses, results in heating and expansion of the element 21 after several seconds. The pull of spring 20a on arm 20 causes opening of the circuit through the controller winding 8 at the contacts 18, whereupon the armature 9 drops out and the contacts 6 and 7 open. The cooling and contraction of the element 21 which follows its disconnection from across the line, results in reclosure of the contacts 18 through the pull of the element, thereby reestablishing the flow of operating current through the controller winding 8. The signals 1 are thereupon operated again, and obviously, subsequent deenergization and reenergization of the winding 8 will cause the signals 1 to be automatically operated on a continuous non-code, although intermittent basis.

As a result of continued closure of the knife switch 16 after an actuated station has run down, the signals 1 will operate indefinitely, under the control of the automatic interrupter. In order to silence the signals and restore the system to the condition of supervision shown in Fig. 1, the dispatching mechanism provides a reset lever 40, pivoted at 41. As best shown in Fig. 8, one arm of the lever 40 extends upwardly beyond the pivot 41 to a point beneath the overhanging end of the lever 35. The free end of the lever arm carries a roller 42 that extends upwardly between oppositely inclined faces 43 and 44 provided by the lever 35, with the roller normally out of engagement with these faces.

The opposite end of the lever 40 extends toward the front portion 25 of the box, and is offset with respect to the pivot 41, to provide an operating portion 45 having a notch 45a therein, in which is received an arm 46 turnable with a shaft 47 extending through the front of the box. The

outer end of the shaft 47 carries a pin 48, and when the door of the box is open, a slotted key carried by a person in authority may be inserted to engage the pin, and thereby turn the shaft 47 to rock the arm 46 either up or down, as viewed in Fig. 4. When the key-operated arm 46 is turned up, with the switch 16 closed (Fig. 5), the resulting turning of the lever 40 on its pivot 41, causes the roller 42 to engage the inclined surface 43. When this occurs, the camming action of the roller 42 turns the lever 35 about the shaft 12a, thereby moving the switch blade 16a out of engagement with the contact 16b, as shown in Fig. 6.

15 In order to test operativeness of the spring motor driving the dispatching mechanism, independently of the signals the lever 40 provides a portion 49 extending parallel to the plane of the code wheel 11 beneath the contacts 10, and having an insulating pin 50 adjacent the end of one coding contact. When the arm 46 is turned down, as viewed in Fig. 4, by the test key, the resulting turning of the lever 40 causes the pin 50, acting through contact 10, to swing the coding arm 30 away from the code wheel through flexure of the engaged contact with the lug 32, as shown in Fig. 7. At the same time, the roller 42 engages the inclined face 44 of switch lever 35, to swing the lever into a position wherein its stud 37 is entirely inside the track cam 39. Subsequent actuation of the dispatching mechanism by the handle 26 has no effect on the system, since supervision is maintained by continued closure of the contacts 10, while the switch 16 is positively maintained in an open position. Release of the arm 46 by the test key restores the arm 30 and lever 35 to the position of Fig. 4, due to the pressure of the flexed contact 10 on the pin 32 and the equalizing action of the springs 36.

40 When it is desired to test the signals 1, upward movement of the lever 46 by the test key from the position of Fig. 4, causes a second pin 51 on the lever extension 49 to close a pair of contacts 52 connected in parallel across the stationary contacts 16b of the knife switch. Since the coding contacts 10 are then closed, in the non-operating condition of the station, closure of the test contacts 52 results in the signals giving one tap, for test purposes. Since turning of the lever 40 which causes the pin 51 to close contact 52 also engages the roller 42 with the face 43 on lever 35, the knife switch 16 is held open while the test is being made.

45 As previously pointed out, the test key is also utilized to open the switch 16 after an actuated station has run down, and thereby silence the signals, which will otherwise operate indefinitely under the control of the automatic interrupter. When the key-operated arm 46 is turned up, with 50 the switch 16 closed, turning of the switch lever 35 by the roller 42 is preceded by closure of the contacts 52, see Fig. 6, thereby preventing arcing at the contacts 16b, as the switch blade disengages these contacts. Since in order to withdraw 55 the key it is necessary to return the shaft 47 to the position of Fig. 4, reopening of the contacts 52 with the switch 16 already opened, has the effect of again placing the resistor 13 in circuit with the controller winding 8. The resulting decrease of the current traversing the winding thereupon causes the armature 9 to drop out, and restore the system to the condition of supervision shown in Fig. 1.

60 It is to be noted that with the parts in the 65 position of Fig. 5, that is with the knife switch

16 closed, the roller 42 is faced on one side by a shoulder 44a adjacent the inclined surface 43. Therefore, only the opposite inclined surface 43 is effective to turn the switch lever 35 through movement of the roller. This arrangement prevents the switch 16 being opened should the key be accidentally turned in the wrong direction when it is desired to silence the signals. With only the surface 43 effective to turn the lever 35 from the position of Fig. 5, the switch 16 can be opened only after the contacts 52 have been closed by a movement of the pin 51 on the lever extension 49, as in Fig. 6.

I claim:

1. A dispatching mechanism for an electrical alarm system, comprising relatively movable contacts normally closed in the non-operating condition of said mechanism, a spring-driven motor adapted to be wound upon actuation of the mechanism, a coding element rotatable by said motor for a predetermined period upon unwinding of said motor to open and close said contacts for the transmission of signal impulses in accordance with the code designation of said element, a switch comprising a blade element carried by a pivoted arm and spaced stationary contacts normally out of engagement with said switch blade, and a cam member rotatable with said coding element for turning said arm to close said switch, in response to turning of said coding element immediately following actuation of said mechanism.

2. A dispatching mechanism for an electrical alarm system, comprising relatively movable contacts normally closed in the non-operating condition of said mechanism, a spring-driven motor adapted to be wound upon actuation of the mechanism, a coding element rotatable by said motor for a predetermined period upon unwinding of said motor to open and close said contacts for the transmission of signal impulses in accordance with the code designation of said element, a switch comprising a blade element carried by a pivoted arm and spaced stationary contacts normally out of engagement with said switch blade, and a cam member rotatable with said coding element for turning said arm to close said switch, in response to turning of said coding ele-

ment, immediately following actuation of said mechanism, said switch being closed in the interval between the initial opening and closing of said coding contacts, to transmit the first impulse of the code.

3. A dispatching mechanism for an electrical alarm system, comprising relatively movable contacts normally closed in the non-operating condition of said mechanism, a spring-driven motor 10 adapted to be wound upon actuation of the mechanism, a coding element rotatable by said motor for a predetermined period upon unwinding of said motor to open and close said contacts for the transmission of signal impulses in accordance with the code designation of said element, a switch comprising a blade element carried by a pivoted arm and spaced stationary contacts normally out of engagement with said switch blade, a cam member rotatable with said coding 15 element for turning said arm to close said switch, in response to turning of said coding element, immediately following actuation of said mechanism, said switch remaining closed after said coding element comes to rest, and means for manually operating said arm independently of said coding element to open said switch.

4. A dispatching mechanism for an electrical alarm system, comprising relatively movable contacts normally closed in the non-operating condition of said mechanism, a spring-driven motor 30 adapted to be wound upon actuation of the mechanism, a coding element rotatable by said motor for a predetermined period upon unwinding of said motor to open and close said contacts for the transmission of signal impulses in accordance with the code designation of said element, a switch comprising a blade element carried by a pivoted arm and spaced stationary contacts normally out of engagement with said switch blade, a cam member rotatable with said coding 35 element for turning said arm to close said switch, in response to turning of said coding element, immediately following actuation of said mechanism, and means for manually rendering said switch blade arm ineffective to be moved by said coding element, when said motor is wound and operated for test purposes.

FERDINAND F. HUMPHREYS.
